DESIGN FOR A REAR VIEW MIRROR AND MOUNTING THEREFOR

John W. Anderson, Gary, Ind., assignor to Pro-
ductive Inventions, Inc., Gary, Ind., a corpora-
tion of Indiana

Application January 19, 1938, Serial No. 74,401

Term of patent 14 years

To all whom it may concern:

Be it known that I, John W. Anderson, a citizen of the United States, residing at Gary, in the county of Lake and State of Indiana, have invented a new, original, and ornamental Design for a Rear View Mirror and Mounting Therefor, of which the following is a specification, reference being had to the accompanying drawing, forming a part thereof.

Referring to the drawing:

Fig. 1 is a perspective view of the front side of

a rear view mirror and mounting therefor embodying my new design;

Fig. 2 is a perspective view of the rear side of the rear view mirror and mounting therefor shown in Fig. 1; and

Fig. 3 is a side elevational view of the mirror element shown in Figs. 1 and 2.

I claim:

The ornamental design for a rear view mirror and mounting therefor, as shown.

JOHN W. ANDERSON.
